US0D1106967S

(12) **United States Design Patent** (10) **Patent No.:** **US D1,106,967 S**
(45) **Date of Patent:** **** Dec. 23, 2025**

(54) **CAR CHARGER ADAPTER**

(71) Applicant: **Dongguan Lipaizhizao Technology Co., Ltd.**, Guangdong (CN)

(72) Inventor: **Rending Long**, Hunan (CN)

(73) Assignee: **Dongguan Lipaizhizao Technology Co., Ltd.**, Dongguan (CN)

(**) Term: **15 Years**

(21) Appl. No.: **29/989,173**

(22) Filed: **Feb. 10, 2025**

(30) **Foreign Application Priority Data**

Jan. 21, 2025 (CN) 202530038118.2

(51) **LOC (15) Cl.** **13-03**

(52) **U.S. Cl.**

USPC **D13/146**

(58) **Field of Classification Search**

(57) **CLAIM**

The ornamental design for a car charger adapter, as shown and described.

DESCRIPTION

FIG. 1 is a perspective view of a car charger adapter showing my new design;

FIG. 2 is another perspective view thereof;

FIG. 3 is a front elevation view thereof;

FIG. 4 is a back elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines depict portions of the car charger adapter that form no part of the claimed design.

1 Claim, 8 Drawing Sheets
